FIG. 2 is a bottom perspective view of the packaging insert in the first folded configuration of FIG. 1.

FIG. 3 is a front view of the packaging insert in the first folded configuration of FIG. 1.

FIG. 4 is a right side view of the packaging insert in the first folded configuration of FIG. 1.

FIG. 5 is a back view of the packaging insert in the first folded configuration of FIG. 1.

FIG. 6 is a left side view of the packaging insert in the first folded configuration of FIG. 1.

FIG. 7 is a top planar view of the packaging insert in the first folded configuration of FIG. 1.

FIG. 8 is a bottom planar view of the packaging insert in the first folded configuration of FIG. 1.

FIG. 9 is a top perspective view of the packaging insert in a second folded configuration.

FIG. 10 is a bottom perspective view of the packaging insert in the second folded configuration of FIG. 9.

FIG. 11 is a front view of the packaging insert in the second folded configuration of FIG. 9.

FIG. 12 is a right side view of the packaging insert in the second folded configuration of FIG. 9.

FIG. 13 is a back view of the packaging insert in the second folded configuration of FIG. 9.

FIG. 14 is a left side view of the packaging insert in the second folded configuration of FIG. 9.

FIG. 15 is a top planar view of the packaging insert in the second folded configuration of FIG. 9.

FIG. 16 is a bottom planar view of the packaging insert in the second folded configuration of FIG. 9; and,

FIG. 17 is a top perspective view of the packaging insert in the second folded configuration of FIG. 9 with a product housed therein.

In FIG. 17, the broken lines show a bottle that forms no part of the claim.
